UNITED STATES PATENT OFFICE

HEINRICH SCHUMACHER, OF HANOVER, GERMANY, ASSIGNOR OF ONE-HALF TO
KARL KÖNNEKER, OF HANOVER, GERMANY

BANDLIKE CALENDAR

Application filed February 29, 1928, Serial No. 258,079, and in Germany May 27, 1927.

This invention has reference to continuous band-like calendars in which the dates are recorded as a continuous register upon a movable band or the like, and it is intended among other important objects and advantages, to so arrange the dates or other instructional, pictorial or similar matter in suitable inspection devices that additional instructional, advertising, or other reading or ornamental matter contained on the back-side of the band, strip or the like, may be viewed simultaneously with the inspection of the particular date or similar matter, contained on the front side of said band or strip of flexible material. Another object of my invention is to provide for the ready exchangeability of the band-like carrier, and to generally improve and facilitate the construction and manipulation of devices of the general kind referred to. Other objects and advantages will appear from the specification in connection with an inspection of the drawings. Calendars containing the dates on a continuous strip or band movable in front of an inspection opening are well known, but my invention is distinguished from the previous art by the fact that the back-side of the strip or band carries advertising, instructing or equivalent informative matter, the said band or strip being moreover adapted to be unwound from a movably disposed loose roll and to be propelled in front of more than one, preferably two inspection openings in such a manner that in one of these openings the dates or the matter on one side of the strip and in the other opening the advertising or other informative matter of the other side of the strip becomes exposed.

The invention is shown by way of exemplification in a preferred embodiment on the accompanying drawing in Figure 1 in front elevation and in Figure 2 in sectional view on the line 2—2 of Figure 1—Figure 3 shows the calendar-band.

In the exemplification shown a stiff back is provided with two openings 4, 6. The calendar-band or strip 8 (Figure 3) carries on one of its sides the dates, and on its back-side advertising or other informative matter. The band is wound up to form a roll

and is displaceably mounted in a small casing or box 10 of card-board or the like and secured to the back wall 2, but without stationarily disposed shaft. The band or strip which rests loosely upon the bottom 10' of the box 10 or is supported for instance between the bottom and the cover of the box resting upon the top of the coiled strip, tape or web 8 is drawn out in the manner indicated in Fig. 2 through the rear opening of the box 10, and is then passed in front of the opening 4 and around a rounded guide rod 13. It is then drawn towards the other side and in front of the opening 6. The band is retained in position by rear walls 12 or the like which are suitably disposed on the device. With this arrangement one side of the band or strip is exposed through the opening 4, while in the opening 6 the other side of the band becomes visible, so that both sides can be readily exposed side by side in the viewing openings 4 and 6. By pulling at the projecting end of the band 8 the band may be moved each day for one section, and will then disclose new advertising or informative matter by the side of the new date.

In view of the fact that the band is loosely wound up, and has no core or interior rolling spindle, the manufacture of such bands is greatly facilitated, and the exchanging of the rolls is simplified. The stiff back-wall 2 may be made of superior material and may present artistic configuration or ornamentation, so that only the band 8 will have to be renewed every year.

I am aware that calendars with continuous date strip wound upon an interior roller or core, and adapted for movement past inspection openings have been proposed heretofore in various modifications. With all these previously known calendars paper rolls were employed adapted for rotation around fixedly journaled shafts, so that the exchanging of such paper rolls became very difficult. There was the additional inconvenience with the devices according to the previous art that the turning of the front side of the band of paper to the back side of the device had to be effected in a rather complicated manner by several guide rollers. In my invention

however, this turning around of the strip is effected merely by causing it to form a loop, and this very easy and convenient turning of the band and its combination with the advertising or informative arrangement are a progress over the previous art.

Variations and modifications of the embodiment herein shown by way of exemplifications are admissible within the scope and spirit of the claims, hereunto annexed.

I claim:

1. In flexible band-like calendars and other indicating and advertising devices the combination with an exhibiting front member and serially and aligningly apertured portions in said member, and a band arranged behind said portions and movable with respect thereof and having indicia on both sides, of a loop-shaped part of said band disposed near one end of the front member, guiding means for the band at the apex of said loop, additional flat guiding means behind the apertured portions, and band-supplying means disposed intermediate the apertured exhibiting portions.

2. In flexible band-like calendars and other indicating and advertising devices the combination with an exhibiting front member and serially and aligningly apertured exhibiting portions in said member and a loop-shaped, lengthwise movable indicating band, carrying indicia on both sides and arranged behind said portions of a band supply intermediate the apertured portions and connected to the loop, and loop-supporting and guiding means engaging the apex of said loop adjacent the apertured portion of the front member.

3. In band-like, flexible calendars and other indicating devices the combination with an exhibiting front member and serially and aligningly apertured exhibiting portions on said member, and a loop of lengthwise movable band-like indicating means carrying indicating matter and arranged behind said portions, of a supply of band-like indicating means connected to said loop and disposed intermediate the apertured exhibiting portions, guiding means behind the unexposed side of the loop and spaced from the apertured exhibiting portions, and a guide at the apex of the loop.

4. In a band-like, flexible calendar and similar indicating device the combination with an exhibiting front member and serially and aligningly apertured exhibiting portions in said member, movable band-like indicating means arranged behind said exhibiting portions and carrying indicia, of a loop-shaped part of said indicating means near one end of the front member, a supply of such indicating means connected to the loop, apertured mounting means for said supply, guiding means on the unexposed portion of the loop and spaced from the apertured ex-

hibiting portions, and guiding means within the apex of the loop.

5. In a band-like, flexible calendar and similar indicating and exhibiting means the combination with an exhibiting front member and serially and aligningly apertured inspecting portions on said member, and movable band-like indicating means behind said inspecting portions, of a coreless, substantially bobbin-like supply of said indicating means intermediate the inspecting portions, and a loop-like connecting indicating part, connecting the first-mentioned band-like indicating means to said supply, an apertured housing for said supply and around the same, substantially flat guiding means behind the unexposed portions of the band-like indicating means and spaced therefrom and from the inspecting portions, and guiding means within the apex of the loop-like part.

6. In a band-like, flexible calendar and similar indicating means, an exhibiting front member, and serially and aligningly apertured inspecting portions in said member, lengthwise movable, flexible indicating means behind said inspection portions and having indicia on both sides, a supply of said indicating means mounted intermediate the inspecting portions, and connected to the indicating means behind said portions, and means to guide said indicating means behind said portions.

7. In a band-like, flexible calendar and similar indicating and exhibiting means, an exhibiting front member, and serially and aligningly apertured inspecting portions on said member, a supply of flexible, substantially band-like indicating means intermediate the inspecting portions, a movable part of said indicating means extending at the rear of the inspecting portions, and comprising a loop-shaped section connected to the supply, transversely disposed indicating sections on both sides of the indicating means and substantially corresponding to the inspecting portions, guiding means for the loop-shaped part and additional guiding means adjacent to and behind the inspecting portions.

HEINRICH SCHUMACHER.
